UNITED STATES PATENT OFFICE.

EDWIN L. CROSBY, OF HIGHLAND PARK, MICHIGAN.

ELECTRIC FURNACE.

1,336,820.

Specification of Letters Patent. Patented Apr. 13, 1920.

Application filed May 3, 1918. Serial No. 232,349.

To all whom it may concern:

Be it known that I, EDWIN L. CROSBY, a citizen of the United States, residing at Highland Park, county of Wayne, State of Michigan, have invented a certain new and useful Improvement in Electric Furnaces, and declare the following to be a full, clear, and exact description of the same, such as will enable others skilled in the art to which it pertains to make and use the same, reference being had to the accompanying drawings, which form a part of this specification.

This invention relates to electric furnaces of the inclosed refractory cylinder type, and has for its object improvements in the construction and arrangement of parts designed to secure efficient mingling of the metal components and more efficient heating, and the reduction, as far as possible, of the disintegrating influences of direct heat of the electric arc employed for heating the metal, upon the refractory walls of the furnace not submerged or washed by the molten mass.

Among the combination of conditions required to be met in this type of furnace is the necessary absence of any mechanical agitator within the furnace chamber, since the high degree of heat employed would cause the rapid disintegration of any such member; moreover, the presence and operation of any such member would almost of necessity involve more or less of a leakage to the atmosphere of the gas generated during the melting of the metal, which, in turn, would result in a high degree of loss of such relatively volatile components as zinc.

In the drawings:

10 Figure 1 is a perspective of my improved type of furnace, showing the electrode adjustment members, as well as the locking system of wedges interposed between the shell and the toothed gear ring, by whose action a portion of the agitation of the furnace contents is brought about.

Fig. 2 is an elevation of my improved device, showing the relative positioning of the electrodes with respect to the shell.

50 Fig. 3 is a side elevation, with portions of the center of the furnace chamber broken away to show the meeting ends of the electrodes within.

Fig. 4 is a plan view of the furnace and its connected parts, half being shown in section.

Fig. 5 is a partly sectional elevation of one form of cooling coil, through which the electrodes pass into the refractory end walls of the furnace.

60

Fig. 6 is a perspective view of the device of Fig. 5.

Fig. 7 is an end view of this form of cooling coil and its connected parts.

Fig. 8 is a partly sectional elevation of a modified or alternative form of cooling shell through which the electrode passes into the furnace shell.

Fig. 9 is a perspective view of the device of Fig. 8.

70

Fig. 10 is an end view of this form of cooling shell.

Fig. 11 is a detail perspective view of one of the supporting roller members for the furnace shell and of its actuating gear mechanism.

The device as a whole rests upon four standards 12, through the top of which engages the pivot pin 13 which connects the strut members 14 therewith. Through each end of each of the strut members passes another pivot pin 15, on which are rotatably journaled the grooved or troughed rollers 16 and 17, which are arranged in pairs in parallel planes, so that the travel ring or track 18 runs smoothly in their grooved portions. These travel rings 18 engage about the drum 19 near the ends thereof, but are spaced therefrom by a series of wedges 20, so that on one side of the drum the wedges 20 under one of the travel rings space it from the shell of the cylinder to the maximum degree required, whereas the wedges under the other ring at that point of the shell's periphery separate it from the surface of the drum by very slight space; the wedge effect on each ring being thus tapered about the periphery of the drum, it results that there are only two points in its complete phase of rotation at which the axis of the drum is in a truly horizontal position. At all other times it is more or less inclined in one direction or the other, right or left as the case may be, as regards the positioning shown in Figs. 1 and 3, thus effecting a wave motion in the mass of molten metal, to which further reference will be made later.

Side by side with the travel ring 18 are located the toothed rings 21, which mesh with the teeth of driving gears 22, which may be actuated by any convenient source of power, such as the reversing mechanism

conventionally indicated at 24, to rotate them and the rings 18 and 21 and the furnace cylinder 19. The rotation imparted may either be continuous or oscillatory, as 5 the conditions of the particular "heat" of metal may require; in some cases less than a complete rotation back and forth will be found desirable. I desire, however, that any 10 type of rotative actuation of the drum, to any degree required, be understood as within the scope of this disclosure.

The furnace drum itself preferably has an outer shell of metal, within which are arranged one or more layers of refractory substance, so that the actual interior dimensions 15 of the melting chamber are much less than those of the exterior dimensions of the drum. Access thereto may be had for charging the furnace, and for pouring of the molten mass, through the hole 23, which is 20 closed by the door 26 when the melting process is going on.

At each end of the furnace drum 19 is located a frame or spider 27, its apertured 25 outer end being arranged coaxially with the drum, so that the outer end of the electrode stem 28, when retracted, can project beyond the spider. Rotatively supported by the end 30 of this spider is a hand wheel 29, whose screw stem 30 is connected with the terminal block 31 into which the current wires 32 lead, and through which the electrode 28 passes in such a way that the terminal block and electrode can be forced toward, or 35 drawn away from, the furnace drum. The interior end of the electrode passes through the end wall of the cylinder to the interior chamber, being separated from the point of the electrode located in the opposite end of 40 the drum by the desired space necessary to give the heating arc required when the current is turned on.

The electrodes pass through cooling shells or coils which are located in the refractory 45 end walls of the furnace, and may be either of the coil type shown at 34 in Fig. 3 and in enlarged detail in Figs. 5, 6 and 7, or of the trunnion type shown at 35 in Fig. 3, and in enlarged detail in Figs. 8, 9 and 10. The 50 inner end of either of these types of cooling members may be spaced from the wall of the furnace 19 by centrally apertured pads or closure pieces 39.

The operation of this device is as follows:

The various components of the alloy desired having been placed within the furnace through the hole 23, the door 26 is fixed in position and the electrodes are individually 60 adjusted by their wheels 29, so that their ends are the desired distance apart. The furnace drum being thus tightly closed and the electric current being turned on, a high degree of heat is quickly generated 65 within the central chamber, and as soon as

the metal component having the lowest melting point begins to liquefy, the rotation of the drum is started by means of the rotating driving gears 22 which mesh with the toothed rings 21. If desired, the rotation 70 may be an oscillatory one, the direction being reversed when a complete revolution of the drum has been accomplished, or it may be such a fraction of a complete rotation as will leave only the proportion 75 of the drum's periphery represented by the width of the door unwashed by the molten mass in the furnace; in either event, that portion of the refractory inner surface of the drum, which at the outset of the 80 "heat" constituted the ceiling or dome of the interior chamber untouched by the molten metal, is "washed" by it as the cylinder rotates, and a certain proportion of excess heat which it has absorbed will in turn be absorbed by the molten metal; and that portion 85 of the inner surface of the cylinder which in the outset computed the bowl or metal-holding portion of the furnace, becomes in turn the ceiling portion, and consequently in turn subjected to the direct heating influence of the exposed electrodes.

This rotation, either continuous or back and forth as may be desired, of course effects to a certain extent the commingling of 95 the components of the alloy so that the tendency of the various components to stratify is offset, but in many instances it would not effect a sufficient mingling of the parts from end to end of the furnace drum, were it not 100 for the axial rocking of the cylinder from end to end, due to its unequal positioning with respect to the rings 18 brought about by the wedging already referred to. Whether the cylinder's turning is complete 105 or oscillatory, however, this constant variation in the position of the central axis of the cylinder effects a wave motion of the molten metal from end to end thereof, which accomplishes the further mingling of the alloys' 110 components to the degree desired. Care, of course, must be taken as to the total quantity of material put into the furnace before the heating is started, so that in allowing for this wave motion from end to end, the 115 top surface of the molten mass will never rise quite to the level of the electrodes. I have illustrated this in Fig. 3 particularly by the dotted lines $x-x$ and $y-y$, which represent the position of the top surface of 120 the molten mass within the heating chamber at the opposite extremes of axial inclination of the cylinder.

What I claim is:

1. In an electric furnace, in combination 125 with a refractory shell member provided with a vapor-tight door, a pair of electrodes adjustably engaging through the ends of said shell coaxially therewith, means for projecting and retracting said electrodes 130

while permitting the maintenance of their coaxial position with respect to the shell member in all positions thereof, a pair of travel rings spacedly and variably engaging about said shell member with respect to the axis thereof, and means for imparting rotative movement thereto, thereby effecting the rotation of the shell about an axis whose position relatively to the horizon 10 is constantly varying during the period of rotation.

2. In an electric furnace, the combination of a rotatable refractory shell, a pair of travel rings engaging thereabout, means for eccentrically spacing said travel rings with respect to the periphery of the shell and to each other, a series of supporting rollers whereon said travel rings move, thereby turning said shell about a constantly variant 20 axis, means for positively causing the rotative movement of said travel rings, and electrode members adjustably engaging through the ends of said shell.

3. An electric furnace, having in combination with a refractory furnace chamber, electrodes adjustably engaging through the ends thereof in alinement with its central axis, means for regulating the positioning of the meeting ends of said electrodes with 25 respect to one another, a pair of travel rings spacedly engaging about said furnace chamber near the ends thereof, wedge members interposed between the wall of the furnace chamber and the inner faces of said 30 rings, whereby said rings are eccentrically disposed with respect to one another and to said furnace chamber, roller members whereon said travel ring members rest, and means for rotatably actuating said travel rings and 35 thereby said furnace chamber.

4. An electric furnace, having in combination with a pair of travel rings disposed in parallel vertical planes, a refractory shell member about whose end portions said 45 travel rings spacedly engage in varying degrees of eccentricity, a plurality of supporting rollers whereon said travel rings rotatably rest, means for imparting rotative movement to said travel rings and thereby 50 to said refractory shell member, and electrode members adjustably engaging through the end walls of said shell member in coaxial relation to one another and to said shell member.

5. In an electric furnace, in combination with a shell member, a pair of adjustable electrode members arranged coaxially thereof, means for regulating the degree of projection of said electrode members into the 55 shell member, cooling members through which the ends of said electrode members

pass to the interior of said shell member and by which said electrode members are spaced from direct contact with the surrounding portions of said shell member, 65 means for rotatively actuating said shell member, and means for varying the rotative axis of said shell member with respect to the horizon while its rotation is in progress.

6. In an electric furnace, the combination 70 of an interiorly refractory shell member having centrally apertured end portions, longitudinally adjustable electrode members engaging through the apertured ends of the shell and arranged to rotate therewith, a 75 pair of ring members spacedly disposed about said shell member at variant distances from the periphery thereof, rotatable supporting rollers whereon said ring members rest, means for rotatively actuating said 80 ring members and with them said shell, thereby effecting a constant variance of the position of its axis relatively to the horizon while the rotative movement is in 85 progress.

7. An electric furnace, having, in combination with a terminally apertured shell member, a pair of ring members eccentrically disposed about the ends thereof, means for rotating the ring members about their 90 common central axis, thereby causing a constant variance from the horizontal of the rotative axis of said shell member, electrode members coaxially engaging in the apertured ends of said shell member, means 95 for regulating the degree of projection and of retraction of said electrode members, and cooling members interposed between said electrode members and the adjacent portions of said shell members.

8. In an electric furnace, in combination with a refractory shell member having centrally apertured ends, adjustable electrode members coaxially engaging through said apertured ends, cooling members engaging 105 about said electrode members in a way to close the space between their outer surfaces and the adjacent edges of the apertures in the shell, a pair of travel rings spacedly engaging about said shell member at variant 110 distances from the periphery thereof, and supporting rollers over which said travel rings move, thereby imparting to said shell member a variance in the position of its axis relatively to the horizon.

In testimony whereof I sign this specification in the presence of two witnesses.

EDWIN L. CROSBY.
